(57) **CLAIM**

We claim the ornamental design for a spotting scope, as shown and described.

DESCRIPTION

FIG. 1 is an isometric view of a spotting scope showing our new design according to a first embodiment;

FIG. 2 is an opposite isometric view thereof;

FIG. 3 is a top plan view thereof;

FIG. 4 is a left side elevation view thereof; a right side elevation view is a mirror image;

FIG. 5 is a bottom plan view thereof;

FIG. 6 is an end elevation view thereof; and

FIG. 7 is an opposite end elevation view thereof.

FIG. 8 is an isometric view of a spotting scope showing our new design according to a second embodiment;

FIG. 9 is an opposite isometric view thereof;

FIG. 10 is a top plan view thereof;

FIG. 11 is a left side elevation view thereof; a right side elevation view is a mirror image;

FIG. 12 is a bottom plan view thereof;

FIG. 13 is an end elevation view thereof; and,

FIG. 14 is an opposite end elevation view thereof.

In FIGS. 1-14, the broken lines are illustrative of environmental structure that forms no part of the claimed design.
